ELECTROLYTIC PROCESS FOR REDUCING SUGARS

Henry Jermain Creighton, Swarthmore, and Ralph A. Hales, Tamaqua, Pa., assignors to Atlas Powder Company, Wilmington, Del., a corporation of Delaware

Application May 21, 1943, Serial No. 487,870

4 Claims. (Cl. 204—77)

1

The present invention relates to an improved process for electrolytically reducing sugars to polyhydric alcohols.

An object of the invention is to improve the efficiency of the electrolytic reduction process by reducing greatly the time necessary to complete the reduction.

Another object is to increase the production of present electrolytic cell equipment by shortening the time of reduction.

A particular object is to improve the efficiency of the process for electrolytically reducing glucose to one or more polyhydric alcohols.

The reduction or hydrogenation of reducible sugars by the electrolytic process is a known and commercially practiced operation. Broadly the process involves the use of an electrolytic diaphragm cell providing separated anode and cathode compartments. The anolyte is a solution of an electrolyte, preferably sulfuric acid, in water. The catholyte is a solution of the sugar to be reduced together with a suitable electrolyte in water. In the catholyte the electrolyte is preferably an alkali metal compound, like sodium sulfate, to which is frequently added an alkali hydroxide. The anode in the process is an electrically conductive material resistant to the corrosive action of the anolyte. In commercial practice the cathode is a rigid plate of lead or zinc. The cathode may also be made of any rigid material and covered with a layer of lead or zinc. Lead cathodes are amalgamated before use. Zinc cathodes are used either amalgamated or unamalgamated. When the anode and cathode are connected to a source of direct current nascent hydrogen is formed at the cathode and sugar in the catholyte solution is thereby reduced to one or more polyhydric alcohols.

By means of this electrolytic process a series of polyhydric alcohols can be made from reducible sugars. Conditions can be selected to produce the polyhydric alcohol which directly corresponds to the sugar, or to produce mixtures of polyhydric alcohols some of which do not correspond directly to the sugar. Thus, from glucose can be made sorbitol which is the corresponding hexitol, or a mixture of mannitol and sorbitol can be made, or the product can be composed of mannitol, sorbitol and other polyhydric alcohols such as hexane pentols. The last two types of products

2

are produced when the catholyte solution is maintained at a relatively high alkalinity while the first type is made at very low alkalinity or with the catholyte in a neutral or acid condition.

This process is more completely described in the patent to H. J. Creighton, No. 1,990,582; and in the patents to R. A. Hales, Nos. 2,289,189, 2,289,190, 2,300,218, and 2,303,210. In commercial practice the catholyte is circulated through the cathode compartment and through a heat exchanger and receiver, as described in the patent to H. J. Creighton, No. 1,990,582, so that the temperature and composition of the catholyte can be controlled throughout the operation.

15 While the above-described process has been commercially successful it has been slow in operation, requiring reduction times in the neighborhood of 200 hours for completion of a large scale reduction. This long period of operation has the effect of requiring large cell capacity for a given volume of production.

The present invention resides in an improvement of the electrolytic process which greatly increases the rate of reduction thereby increasing 20 the productivity of cell equipment. Operating in accordance with the invention results in increasing up to ten-fold or more the rate of reduction of the process. Another advantage of the present process resides in operating economies 25 made possible in temperature control by virtue of the fact that the process is conducted at a higher temperature than the known process.

Broadly the invention employs a higher operating catholyte temperature than that previously 30 employed, plus a higher cathode current density than that previously employed, the temperature and current density values being correlated according to a definite plan which takes into account two other process variables, namely, the concentration of sugar in the catholyte and the relation of the area of the cathode to the volume 35 of the catholyte.

In the prior practice of the electrolytic process, the catholyte was maintained at a temperature 40 of about 68° or 69° Fahrenheit and the current density at the cathode was about 1 ampere or less per square decimeter of cathode surface. Higher temperatures were tried and found unsatisfactory in the prior process because they impaired the 45 quality of the product through darkening the

color, and producing organic acids in objectionable quantities. Raising the temperature alone did not improve the rate of reduction. A further effect of raising temperature alone was to give products of different composition than the normal process. It had also been attempted to increase the rate of reduction by raising the current density at the cathode without making any change in the catholyte temperature. The result of this attempt was that no increase in the rate of reduction occurred and the current efficiency of the process dropped off sharply.

In the process of the invention the catholyte is maintained at a temperature of at least 72° Fahrenheit and not over 135° Fahrenheit. Raising the temperature alone, however, produces only the disadvantages just discussed. We have found it to be possible to compensate for this higher operating temperature by increasing the current density at the cathode to a value of 1.1 ampere or higher per square decimeter of cathode surface. The upper limit of current density is a practical one because extremely high current densities involve excessive power costs. In general current densities should not exceed 10 amperes per square decimeter of cathode surface for this reason. It does not suffice to select any two values of temperature and current density at random but these variables must be correlated to compensate for one another. We have further found that the particular values of temperature and current density to be used depends in a given case on the concentration of sugar in the catholyte and also on the ratio of cathode area to catholyte volume.

For convenience in presentation, the relationship of these four operating variables has been broken down into temperature as one element and the expression "grams initial sugar per ampere" as the other element. The expression "grams initial sugar per ampere" is derived by factoring the fraction

$$\frac{C_0}{R \times CD}$$

wherein, C_0 is the number of grams of sugar per liter of catholyte, R is the ratio of the cathode area in square decimeters to the volume of the catholyte in liters, and CD is the current density at the cathode in amperes per square decimeter of cathode surface. Supplying the values of the symbols in the fraction gives

$$\frac{\text{grams sugar}}{\text{liter}} = \frac{\text{dm.}^2}{\text{liter}} \times \frac{\text{amperes}}{\text{dm.}^2}$$

which on factoring becomes

$$\frac{\text{grams sugar}}{\text{amperes}}$$

or "grams initial sugar per ampere." The relationship between temperature and grams initial sugar per ampere for successful operation is an empirical one which can, however, be described accurately for the range of practical operating conditions of the process. A graphic definition of this relationship is presented hereinafter.

Referring now to the accompanying drawings wherein like numerals designate corresponding parts,

Figure 1 is a diagrammatic representation of an electrolytic cell which may be used in practicing

the present invention, the cell body and diaphragms being shown in vertical section.

Figure 2 is a sectional view of the cell taken on the line II—II of Fig. 1.

Figure 3 is a semi-logarithmic graph made by plotting certain operating variables of the process as explained hereinafter.

Referring now specifically to Figures 1 and 2, the electrolytic cell for use in practicing the present invention comprises a cell body 25, which may be made of ceramic material, wood or the like. This body is a box-like structure open at the top. The construction must be such that the cell will retain aqueous solutions without leakage and resist the corrosive actions of strong electrolytes. Disposed within the body 25 of the cell are diaphragms 26, which also are of box-like structure, open at the top. The diaphragms are made of semi-permeable material so as to prevent liquids on opposite sides thereof from freely intermixing but offering little resistance to the passage of charged ions through the walls. A suitable material for the construction of the diaphragms is sintered aluminum oxide such as the material sold under the trade-mark "Alundum." In the form of cell illustrated in Figure 1, two diaphragms are employed. Suspended in the diaphragm boxes 26 are the anodes 27, which are preferably made of chemical lead, although other current conductive, corrosion resistant materials can be used. Outside of the diaphragm boxes 26 and in the main body of the cell 25, cathodes 28 are positioned. The cathodes are rigid plates with metallic surfaces such as lead or zinc. The cathodes can be made of solid metal or of suitable base material covered by a layer of such metal. When the cathode surface is lead, it is amalgamated by dipping in or rubbing with mercury or dipping in mercuric nitrate solution before using. Where the surface is of zinc, the cathode can be used either with or without amalgamation. It will, thus, be seen that the cell body 25 is divided by means of the diaphragms 26 into anode and cathode compartments. The anode compartments are provided with the anolyte 30 which is an aqueous solution of a current carrying electrolyte, preferably sulphuric acid. The cathode compartment, which is actually the body of the cell outside the diaphragms 26, is provided with the catholyte 29, which is an aqueous solution of the sugar to be reduced and a current carrying alkali metal electrolyte.

The anodes 27 and cathodes 28 of the cell are connected respectively to the positive and negative terminals of a source of direct current. When the solutions are placed within the cell and an electric current is passed between the anodes and cathodes, the sugar in the catholyte is reduced or hydrogenated to form the polyhydric alcohol product.

The concentration of sugar will depend upon its solubility in the catholyte 29. In the case of glucose, the preferred concentration is between 200 and 700 grams per liter. The preferred sugar is glucose, because of the valuable products obtained from it, although other reducible monosaccharides such as fructose, mannose, the mixture of glucose and fructose obtained by the inversion of sucrose, the mixture of glucose and galactose obtained by the inversion of lactose, and pentoses, and reducible disaccharides, such as lactose, can be used.

The ratio of cathode area to catholyte volume is susceptible of wide variation but for practical purposes the range of 0.25 to 10 square decimeters

of cathode surface per liter of catholyte is preferred. This ratio can be controlled at a selected value by varying the area of the cathodes for a given catholyte volume, or by varying the amount of catholyte processed, or by varying both of them. The most practical method for a given cell construction consists in changing the catholyte volume.

In reductions at the temperature of the invention, particularly in the upper part of the range, and where the catholyte is strongly alkaline it is advantageous to employ a protective float on the upper surface of the catholyte to prevent contact with air. Suitable means for this purpose are disclosed in the application of K. R. Brown, Serial Number 458,820, filed September 18, 1942, now abandoned.

The temperature of the catholyte may be adjusted initially by heating or cooling, as required, before starting the reduction. The reduction process results in the generation of heat in the solutions and during the operation of a cell the catholyte temperature is kept at the desired value by cooling. The temperature control may be accomplished by conventional means such as immersing the cell in a bath of liquid, by flowing a liquid through coils immersed in the cell solutions, by circulating the cell solutions through external heat exchangers, etc. In large scale installations it is customary to employ external heat exchangers for temperature control, as described for example in the patent to H. J. Creighton, No. 1,990,582.

Referring now to Figure 3, the graph is of the semi-logarithmic type with temperature in degrees Fahrenheit represented arithmetically as the abscissa and grams initial sugar per ampere represented logarithmically as ordinate. The area bounded by the line ABCDEA contains the points which represent the range of operative ratios of temperature to grams initial sugar per ampere when current densities of at least 1.1 amperes per square decimeter of cathode surface are used. For a given set of conditions of sugar, catholyte alkalinity (or acidity), and cathode material, substantially the same product can be made at the ratios of temperature to grams initial sugar per ampere which lie on lines parallel to the line BC. For example, the line FG represents ratios of temperature to grams initial sugar per ampere for making a high purity sorbitol from glucose with an amalgamated zinc cathode and with a catholyte containing from 0 to 2.0 grams NaOH per liter. Similarly, the line HI represents ratios for making mannitol and a noncrystallizing sorbitol syrup from glucose with an amalgamated lead cathode and with a catholyte containing from 10 to 20 grams NaOH per liter.

For the same sugar, catholyte alkalinity (or acidity) and cathode material, variations in the polyhydric alcohol composition of the product occur when ratios of temperature to grams initial sugar per ampere are selected which lie on different lines parallel to BC in Figure 3. As between two reductions employing ratios lying on different lines parallel to BC, that which is farther from BC will produce a product higher in polyhydric alcohol obtainable directly by hydrogenating the carbonyl group of the selected sugar to a carbinol group. Where the selected sugars are hexoses the directly obtainable polyhydric alcohols are hexahydric alcohols also called hexitols. An aldo-hexose yields only one hexitol by direct hydrogenation under non-isomerizing conditions while a keto-hexose yields two hexitols by direct

hydrogenation. For convenience in description the polyhydric alcohols obtainable by direct reduction of a sugar are referred to as the "specific" hydrogenation products of that sugar to distinguish from so-called "non-specific" products which are polyhydric alcohols obtainable only by more complex reactions which may include, for example, isomerization of the sugar, hydrogenation of carbinol groups to hydrocarbon groups, and carbon chain cracking. From glucose, for example, the reduction using a ratio falling on the line farther from BC will give a product containing more sorbitol than an otherwise identical reduction using a ratio falling on the line nearer to BC. The reduction employing a ratio falling on the line nearer to BC will give relatively more of the nonspecific hydrogenation products, which from glucose are mannitol and non-hexitol compounds chiefly hexane pentols. These effects will become more apparent from a consideration of the examples.

The invention provides a range of novel operating conditions throughout which the advantages of faster rate of reduction and improved efficiency in temperature control are obtained. Furthermore, the invention provides a series of operating ratios of temperature to grams initial sugar per ampere for making products of like composition at fixed conditions of sugar, catholyte alkalinity (or acidity) and cathode material.

For convenience in presentation and for better comparison the following examples are tabulated. Glucose solutions were reduced in each example, 75 g. of sodium sulfate per liter being added to carry the current. An "Alundum" diaphragm separated the catholyte from the anolyte which was a dilute aqueous solution of sulfuric acid.

The tabulated items are:

Ratio.—The ratio of the surface area of the cathode, in square decimeters, to the volume of the cathode, in liters.

C. D.—The current density in amperes per square decimeter of cathode area.

Temp.—The temperature in degrees Fahrenheit of the catholyte during reduction.

P. N.—The pyridine number of the product. This value is a measure of the sorbitol content of a composition based on the formation of the sorbitol-pyridine complex according to the method outlined by Strain in J. A. C. S. 56, 1757. The value generally parallels the percentage sorbitol content, the P. N. being numerically smaller than the percentage figure.

Man.—The percentage of mannitol in the product.

Yield.—The percentage of total polyhydric alcohol material actually obtained in the reduction with reference to the theoretical yield.

g./dm.²/hr.—Grams of sugar reduced per square decimeter of cathode area per hour. This value is a measure of the time efficiency of the reduction. The figures are computed with reference to 99% sugar reduction except where otherwise noted.

g./amp.—Grams initial sugar per ampere, the value of the expression

Grams initial sugar per liter of catholyte

Ratio $\times$ *C. D.*

Examples 1 to 10 inclusive employed amalgamated lead cathodes, floats on the catholyte in the receiver, and an alkali concentration initially 10 g. NaOH per liter which was allowed to increase to 20 g. during the reduction and was

7 maintained thereafter at the latter value by neutralization as required.

The following table gives examples of reductions according to the invention. In Examples 1 and 2 the catholyte contained initially 500 g. glucose per liter while in the other examples the catholyte contained initially 325 g. glucose per liter.

Table I

Example	Ratio	C. D.	Temp.	P. N.	Man.	Yield	g./dm. ³ /hr.	g./amp.
1	1.21	4.0	81	40.5	17.4	91.6	4.75	103
2	1.21	10.0	100	18	14.9	90.5	13.2	41.3
3	1.21	4.0	85	52	17.6	93.1	5.26	67.2
4	1.21	2.0	75	49	20.0	95.9	2.40	134
5	2.0	2.0	81	54	17.8	95.3	2.60	81.3
6	2.0	4.0	93	40	15.4	91.1	5.65	40.6
7	2.0	6.0	95	55	14.6	91.0	6.70	27.1
8	2.0	6.0	110	12	1.5	86.2	9.43	27.1

For comparison with the examples in Table I which are in accordance with the present invention, the following table gives two examples of reductions at values of temperature and current density outside of the values contemplated by this

8 tions of the other variable factors of the reduction.

In the following table the three reductions according to the invention were all carried out with catholytes at an initial concentration of 325 g. glucose per liter. The three examples (11, 12 and 13) were reductions in which an initial alkalinity of 5.0 g. NaOH per liter of cath-

lyte was allowed to increase to 10.0 g. per liter at which value it was kept by neutralization as required. Examples 11 and 12 were conducted with amalgamated zinc cathodes while in Example 13 an amalgamated lead cathode was used.

Table III

Example	Ratio	C. D.	Temp.	P. N.	Man.	Yield	g./dm. ³ /hr.	g./amp.
11	2.0	4.0	97	31.5	11.9	85.6	5.4	40.6
12	2.0	4.0	100	0	1.5	81.4	6.2	40.6
13	2.0	4.0	100	54	15.3	90.0	6.0	40.6

invention. Example 9 had a catholyte concentration of 500 g. glucose per liter and the catholyte in Example 10 had 325 g. glucose per liter. These reductions were both conducted at the same alkalinity as the examples in Table I.

Notable in the foregoing examples are the sharp rise in rate of reduction and the radical change in the composition of the product of Example 12 as compared to Example 11. These two examples were similar in all respects except tem-

Table II

Example	Ratio	C. D.	Temp.	P. N.	Man.	Yield	g./dm. ³ /hr.	g./amp.
9	1.21	1.0	69	42.5	16.0	88.5	1.62	413
10	1.21	1.0	81	0	1.2	78.8	1.48	269

In Example 9 both temperature and current density were below the values used in following the present invention. The rate of reduction of sugar is markedly lower than the rates in any of the examples in Table I. For instance Example 2 shows a rate of reduction over eight times that of Example 9. Note the increase in the rate of reduction obtained even by concurrently raising the temperature to 75° F. and the current density to 2.0 as in Example 4 as compared to the rate obtained at 69° F. and 1.0 ampere in Example 9. Example 10 shows a decrease in the rate of reduction compared to Example 9 when the temperature is raised to 81° F. and the current density held at 1.0 ampere. Note also the 0 P. N. and 1.2% mannitol of the product of Example 10.

Examples 1 and 6 following the invention and Example 9 following the previous practice all produced substantially the same product, as far as sorbitol (determined as P. N.) and mannitol are concerned, although the temperatures and current densities of these examples were widely different. These examples are illustrative of the variation of temperature and current density to produce similar products under various condi-

50 tions. In Example 11 the temperature was 97° F. while in Example 12 the temperature was 100° F. The difference in cathodes is strikingly shown in Examples 12 and 13; otherwise similar, where the change from an amalgamated zinc cathode in Example 12 to an amalgamated lead cathode in Example 13 produced a slight lowering of the rate of reduction but a very great change in the composition of the product. Example 12 gave a product of P. N. 0 and 1.5% mannitol. While the P. N. of 0 does not necessarily show complete absence of sorbitol it does show very low sorbitol content. Example 13 exhibits a great increase in both sorbitol and mannitol content of the product.

Table IV gives further examples of reductions in accordance with the invention, in which a catholyte containing 325 g. glucose per liter was reduced at an alkalinity initially 0.5 g. NaOH per liter which was allowed to rise to 1.5 g. per liter in the course of reduction and was kept between these values by neutralization as required. In Examples 14 to 17 amalgamated zinc cathodes were used while in Example 18 an amalgamated 70 lead cathode was used.

Table IV

Example	Ratio	C. D.	Temp.	P. N.	Man.	Yield	g./dm. ² /hr.	g./amp.
14-----	2.0	4.0	81	76	0	92.3	3.8	40.6
15-----	2.0	4.0	90	63	0	91.0	5.4	40.6
16-----	2.0	4.0	120	26	3.0	95.0	5.4	40.6
17-----	2.0	6.0	90	75.5	0	93.6	5.4	27.1
18-----	2.0	4.0	90	68.5	0.3	92.4	1.9	40.6

Examples 14 and 17 gave a product with substantially the same P. N. and mannitol content although Example 14 was run with a catholyte temperature of 81° F. and at a current density of 4 amperes while Example 17 was run at 90° F. and 6 amperes. However, Example 17 shows a rate of reduction over 40% higher than Example 14. Example 18 shows a relatively low rate of reduction attributable to the use of an amalgamated lead cathode at the low alkalinity under which this run was conducted. Example 16 shows the use of 120° F. as the catholyte temperature along with a current density of 4.0, the product having a low P. N. value and a low mannitol content and being composed largely of other hexitols and related materials.

The following example of a run at ordinary temperature and current density shows the results of a low alkalinity reduction (0.5-1.5 g. NaOH per liter of catholyte as in Examples 14 to 18) with an amalgamated zinc cathode and a glucose concentration of 325 g. per liter of catholyte.

Table V

Example	Ratio	C. D.	Temp.	P. N.	Man.	Yield	g./dm. ² /hr.	g./amp.
19-----	2.0	1.0	60	76	0	92.0	1.0	163

Note that the rate of reduction of Example 18, with an amalgamated lead cathode, is 90% higher than the rate attained in this Example 19 in spite of the fact that the latter run was made with an amalgamated zinc cathode. It is also interesting to observe that substantially the same P. N. and mannitol content were found in the product of Example 19 as were found in the products of Examples 14 and 17.

Two further examples follow to show the comparative results in Example 20, a run according to the invention, and Example 21, a run at ordinary temperature and current density. The two examples were conducted in non-circulated cells, at 325 g. glucose per liter of catholyte, 20 g. NaOH per liter of catholyte, and with amalgamated zinc cathodes. The cathodes were corrugated or scored on their surfaces and the actual active cathode area was substantially double the area of a smooth (plane) cathode of similar dimensions. The values given for Ratio and C. D. are based on the plane surface areas of the corrugated cathodes. Throughout this specification and in the claims the term cathode area is used to signify the plane area of the cathode. Reduction was carried to a point at which 90% of the initial glucose had been reduced.

The improvement in the rate of reduction of Example 20 as compared with Example 21 is attributable to the increase of temperature from 68° F., in Example 21, to 90° F., in Example 20, and to the simultaneous increase in current density from 1.0 in Example 21, to 2.6 to 2.7 in Example 20.

The examples of reductions following the present invention show a few of the possible temperature and current density values. It is preferred to conduct the reductions with the temperature between 80° and 110° F. and with the current density between 2 to 10. At temperatures above 110° F. the organic acid and color of the product are higher and the product is thereby rendered less desirable for many purposes than one produced at a lower temperature. Further increases in current density are generally undesirable because of the increase in power cost and the falling off of current efficiency.

The foregoing 21 examples have been plotted on the graph of Figure 3, the points representing the values of temperature and grams initial sugar

per ampere being indicated by the respective example numbers.

While glucose was reduced in each of the foregoing examples the invention is not limited in this respect but may be applied to the reduction of other reducible sugars and mixtures of reducible sugars.

It is further to be understood as within the concept of this invention to maintain the conditions of high temperature and current density either throughout a reduction or during a substantial part thereof. Moreover, it is not necessary to keep either temperature or current density at a constant value in practicing the invention and desirable effects and economies can be obtained in many instances by running certain parts of a reduction under different conditions of temperature and current density than the rest of the reduction.

Having now described the invention what is claimed is:

1. In the process of electrolytically reducing glucose in a cell provided with a metal plate cathode and an anode in cathode and anode compartments respectively separated by a diaphragm, and having an electrolyte solution in the anode compartment, the steps comprising employing a solu-

tion of glucose and an alkali metal electrolyte in water as the catholyte solution in the cathode compartment of the cell, said solution containing from 200 to 700 grams glucose per liter, the ratio of the area of the cathode of the cell to the volume of said catholyte solution being from 0.25 to 10 square decimeters per liter, passing an electric current between said anode and said cathode and through said catholyte solution to reduce the glucose therein to polyhydric alcohol, maintaining a current density of from 2 to 10 amperes per square decimeter of surface of said cathode during a substantial part of the reduction, and simultaneously maintaining said catholyte solution at a temperature of from 80° to 110° F.; said current density and catholyte temperature being correlated, taking into account the initial concentration of glucose in said catholyte, and the ratio of area of said cathode to the volume of catholyte, so that the point defined by plotting the arithmetic value of the temperature in degrees Fahrenheit as abscissa against an ordinate which is the logarithmic value of the expression

$$\frac{C_0}{R \times CD}$$

wherein

C_0 is the initial concentration of glucose in the catholyte solution in grams per liter

R is the ratio of cathode area to the volume of catholyte solution in square decimeters per liter

CD is the current density at the cathode in amperes per square decimeter of cathode surface, falls within the area ABCDEA in the accompanying graph Figure 3.

2. In the process of electrolytically reducing glucose in a cell provided with an amalgamated lead cathode and an anode in cathode and anode compartments respectively separated by a diaphragm, and having an electrolyte solution in the anode compartment, the steps comprising employing a water solution of 200 to 700 grams glucose per liter, sodium sulfate and from 10 to 20 grams per liter of sodium hydroxide as the catholyte solution in the cathode compartment of said cell, the ratio of the area of the cathode of the cell to the volume of said catholyte solution being from 0.25 to 10 square decimeters per liter, passing an electric current between said anode and cathode and through said catholyte solution to reduce the glucose therein to a mixture of polyhydric alcohols of low sorbitol content, maintaining a current density of 2 to 10 amperes per square decimeter of surface of said cathode during a substantial part of the reduction, and simultaneously maintaining said catholyte solution at a temperature of 80 to 110° F.; said current density and catholyte temperature being correlated, taking into account the initial concentration of glucose in the catholyte and the ratio of area of said cathode to the volume of catholyte, so that the point defined by plotting the arithmetic value of the temperature in degrees Fahrenheit as abscissa against an ordinate which is the logarithmic value of the expression

$$\frac{C_0}{R \times CD}$$

wherein

C_0 is the initial concentration of glucose in the catholyte solution in grams per liter

R is the ratio of cathode area to the volume of catholyte solution in square decimeters per liter

CD is the current density at the cathode in amperes per square decimeter of cathode surface, falls substantially on the line HI in the accompanying graph Figure 3.

- 5 3. In the process of electrolytically reducing glucose in a cell provided with an amalgamated zinc cathode and an anode in anode and cathode compartments respectively separated by a diaphragm, and having an electrolyte solution in the anode compartment, the steps comprising employing a water solution of 200 to 700 grams glucose per liter, sodium sulfate, and from 0 to 2 grams per liter of sodium hydroxide as the catholyte solution in the cathode compartment of said cell, the ratio of the area of the cathode of the cell to the volume of said catholyte solution being from 0.25 to 10 square decimeters per liter, passing an electric current between said anode and cathode and through said catholyte solution to reduce the glucose therein to a polyhydric alcohol product of high sorbitol content, maintaining a current density of 2 to 10 amperes per square decimeter of surface of said cathode during a substantial part of the reduction, and simultaneously maintaining said catholyte solution at a temperature of 80 to 110° F.; said current density and catholyte temperature being correlated, taking into account the initial concentration of glucose in the catholyte and the ratio of area of said cathode to the volume of catholyte, so that the point defined by plotting the arithmetic value of the temperature in degrees Fahrenheit as abscissa against an ordinate which is the logarithmic value of the expression

$$\frac{C_0}{R \times CD}$$

wherein,

40 C_0 is the initial concentration of glucose in the catholyte solution in grams per liter

R is the ratio of cathode area to the volume of catholyte solution in square decimeters per liter

CD is the current density at the cathode in amperes per square decimeter of cathode surface, falls substantially on the line FG in the accompanying graph Figure 3.

- 45 4. In the process of electrolytically reducing a 50 reducible sugar selected from the class consisting of monosaccharides and disaccharides in a cell provided with a metal plate cathode and an anode in cathode and anode compartments respectively separated by a diaphragm, and having an electrolyte solution in the anode compartment, the steps comprising employing a solution of the reducible sugar and an electrolyte in water as the catholyte solution in the cathode compartment of said cell, said solution containing from 200 to 700 grams of the sugar per liter, the ratio of the area of the cathode of the cell to the volume of said catholyte solution being from 0.25 to 10 square decimeters per liter, passing an electric current between said anode and said cathode and through said catholyte solution to reduce the sugar therein to polyhydric alcohol, maintaining a current density of 2 to 10 amperes per square decimeter of surface of said cathode during at least a substantial part of the reduction, and simultaneously maintaining said catholyte solution at a temperature of 80° to 110° F.; said current density and catholyte temperature being correlated, taking into account the initial concentration of sugar in the catholyte and the ratio of area of said cathode to the volume of catholyte, so that the point defined by plotting

the arithmetic value of the temperature in degrees Fahrenheit as abscissa against an ordinate which is the logarithmic value of the expression,

$$\frac{C_0}{R \times CD}$$

wherein,

C_0 is the initial concentration of sugar in the catholyte solution in grams per liter.

R is the ratio of cathode area to the volume of catholyte solution in square decimeters per liter.

CD is the current density at the cathode in amperes per square decimeter of cathode surface, falls within the area ABCDEA in the accompanying graph Figure 3.
